UNITED STATES PATENT OFFICE.

OTTOMAR MEINEL AND ERNST MEINEL, OF GOHLIS, NEAR LEIPZIG,
GERMANY.

MUSICAL DRUM.

SPECIFICATION forming part of Letters Patent No. 770,300, dated September 20, 1904.

Application filed March 30, 1903. Serial No. 150,306. (No model.)

To all whom it may concern:

Be it known that we, OTTOMAR MEINEL and ERNST MEINEL, both subjects of the King of Saxony, both residing at No. 15 St. Privat street, Gohlis, near Leipzig, in the Kingdom of Saxony, German Empire, have invented a new and useful Improvement in Musical Drums, of which the following is a specification.

- 10 Our invention relates to improvements in musical drums, either stationary or portable; and the objects of our improvement are, first, to provide a suitable support for it within or without the drum for receiving a revoluble perforated note-disk and carrying several spring-pressed elastic hammers; second, to provide means for taking up the pressure from the hammers on the note-disk; third, to provide means for driving the note-disk, and, 15 fourth, to so arrange the whole that the revoluble note-disk can be replaced by another one. We attain these objects by the mechanism illustrated in a mode of execution in the accompanying drawings, in which—
20 Figure 1 is a plan of the musical drum, the cover being removed; and Fig. 2 is a vertical section through the same on the broken line M M in Fig. 1.

Similar letters of reference refer to similar parts in both views.

Within the casing *a* at a certain distance from its center a board *c* is secured, which carries a pin *d* for the revoluble note-disk *e*, an arm *t*, a combined bearing and support *f*, 35 a bearing *f'*, and a support *v*. The revoluble disk *e* rests on the support *f* and two guiding-rollers *g* *g*, of which the one *g* turns on a pin secured to the drum-casing *a* and the other roller *g* on a pin held by the arm *t*. The 40 note-disk *e* has three concentrical series of rectangular perforations *m* *m* and along the periphery a series of notches *p*. In the two bearings *f* *f'* a shaft *g* is secured, on which three two-armed levers *u* *u* are mounted to turn independently of each other. They may be prevented from shifting on the shaft by collars or the like. The one arm of each lever *u* is provided with a nose *i*, which can engage the several perforations *m* *m* of the respective con-

centric series. The other arm is rigidly connected with the elastic helve *h* of the hammer *k*. The note-disk *e* can be revolved by a handle *n* on the outside of the drum-casing *a* by means of a shaft *w* and a gear-wheel *o*, the teeth of which engage in the notches *p*. The shaft *w* is mounted to turn in the support *v* and a suitable bearing in the drum-casing *a*.

It will be evident that the weight of each hammer *k* will cause the respective nose *i* to bear from below against the under side of the note-disk *e*. For taking up this pressure of the noses *i* a horizontal shaft *r*, carrying three sharply-edged guiding-disks *x* *x*, is mounted to turn in an extension of the support *f* and in a bearing *y*, which is secured on the upper end of the pin *d*. The guiding-disks *x* *x* bear on the upper side of the note-disk *e* and prevent the latter from rising. When the note-disk *e* is revolved by the handle *n*, each nose *i* will engage in the several perforations *m* of the respective series and allow the hammer *k* to drop and strike against the bottom or skin *b*, when the latter will sound. So as to increase the strength of the blow, springs *l* are preferably fastened on the board *c*, which bear against the nosed arms of the levers *u* *u*. During the revolution of the note-disk *e* each nose *i*, owing to its tapering shape, will be again forced downward out of the perforation *m* and raise the hammer *k*. Fig. 2 represents two hammers *k* *k* in the upper and lower positions, respectively. The various perforations *m* of the note-disk *e* are of course so arranged that the note-disk *e* requires to be replaced by another one after the cover or skin *s* and also the shaft *r* have been removed.

Where it is so preferred, the board *c* may be secured without the drum either on its casing *a* or in a suitable frame.

In case the musical drum is portable it is evident that the mechanism within the same may be left alone, and the common sticks can be used for sounding the drum.

Having now described our invention, what we wish to secure by Letters Patent of the United States is—

A toy drum having a cross-board mounted therein, bearings mounted on said board to

support a shaft, a series of hammers mounted on said shaft and having tailpieces extending to the rear of the same with upwardly-turned noses, the heads of said hammers being adapted to contact with the interior of the lower drum-skin, a note-disk having orifices, mounted above said hammer-tailpieces and adapted to rest on the top of one of the said bearings, supporting-rolls suitably mounted within the drum to support the said disk at other points and a pressure-arm to rest thereon, and springs adapted to force the hammer-heads against the drum-skin, when the nose of said hammer

enters an orifice of the note-disk, and a hand-crank and means in connection therewith for rotating the said note-disk when the said crank is revolved from the exterior of the drum substantially as described. 15

In witness whereof we have hereunto set our hands in presence of two witnesses.

OTTOMAR MEINEL.
ERNST MEINEL.
